UNITED STATES PATENT OFFICE.

JOSEPH H. GRAY, OF ST. JOSEPH, MISSOURI.

DEVICE FOR ALIGNING WHEELS.

Application filed March 12, 1927. Serial No. 174,958.

This invention relates to a device for aligning the front wheels of an automobile.

An object of the invention is the provision of a device adapted to be employed in connection with the front wheels of an automobile and having a scale and indicator for disclosing the distance between the forward part of the front wheel, said device being adapted to be carried around by the wheels when the vehicle is moved forwardly until a point is reached at the rear of the initial position where the device is at substantially the same height from the floor as it was in the initial position, the final position of the indicator disclosing the differences between the distance of the front portion of the wheel and the rear portion and also the amount of correction necessary if the wheels are out of alignment.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claim.

In the drawings:

Figure 1 is a view in perspective of my aligning device shown applied to the wheels of an automobile,

Figure 2 is a longitudinal side view of the device,

Figure 3 is a transverse vertical section taken along the line 3—3 of Figure 2, and

Figure 4 is a fragmentary vertical section of the aligning device.

Referring more particularly to the drawings, 10 and 11 designate a pair of front wheels of an automobile 12 which are adapted to be tested for proper alignment by the device forming the subject-matter of the present application.

The aligning device consists of a pair of bars 13 and 14 having their inner ends slidably mounted on each other and in substantially the same vertical plane. A U-shaped bracket 15 is secured, at 16, to the inner end of the bar 13 and has its bridging portion embracing the inner end of the bar 14. The bracket 17, secured at 18 to the bar 14, has its bridging end embracing the inner end of the bar 14 and is adapted to

engage a stop in the form of a pin 19 secured to the extreme inner end of bar 13. The bracket 15 is adapted to engage a pin 20 secured to the extreme inner end of the bar 14.

Each of the bars, as shown at 21, at their inner ends are provided with chambers and a spring 22 is enclosed by the chambers and has one end, as shown at 23, secured to the bar 13 and its other end secured at 24 to the inner end of the bar 14. The spring is of the spiral type and is adapted to move the inner ends in close association, thereby forcing the outer ends of the bars outwardly for a purpose which will be hereinafter described.

A chain 25 is connected to the inner end of the bar 14 while a chain 27 is connected to the outer end of said bar. Each of the chains is provided with a tip 29 adapted to engage the ground.

A flat strip of material 30 is secured in any approved manner to the outer face of the bar 14 and is provided with a scale, as shown at 31. A pointer 32 is adapted to be moved over the scale and is connected to a clamping device, generally designated by the numeral 33. The pointer 32 is formed at one end of an arm 34 which is resiliently maintained in predetermined position with respect to a second arm 35 by means of a spring 36. The inner end of the arm 35, as shown at 37, is adapted to be received within a groove 38 formed along the lower face of the bar 14 and is adapted to engage a flange 39, depending from the bar 14. The pointer 32 is adapted to engage the outer face of the member 30.

A tire-engaging member 40 is secured to the outer end of the bar 14 while a tire-engaging member 41 is secured to the outer end of the bar 13. These members are located in substantially the same horizontal plane.

The operation of my device is as follows: The bars 13 and 14 are moved inwardly and over each other against the tension of the spring 22 until the tire engaging members 40 and 41 will engage the inner rounded surfaces of the tires 10 and 11. The bars are then released and the spring forces the bars outwardly, moving the ends of the tire engaging members 40 and 41 into engagement with the tires. The pointer 32 is then released by operating the arms 34 and 35 and moved along the scale 31 until it is aligned

with the inner edge 42 of the bar 13. The automobile is then moved forwardly and the aligning device is carried around with the wheels since the bars are forced outwardly by the spring 22 and the tire engaging members 40 and 41 are maintained in rigid engagement with the wheels. As soon as the aligning device reaches a point which is at substantially the same height above the floor 10 as the initial position and the points 29 of the chains again touch the floor, the automobile is stopped. The position of the pointer 32 is then noted with respect to the inner end 42 of the bar 13. If the difference 15 between the initial position and the final position of the aligning device is the normal difference the wheels are then considered as properly aligned. However, any greater difference than the normal will indicate the disalignment of the wheels which is corrected in the usual manner. The horizontal position of the aligning device is initially determined when the tips 29 touch the floor.

20 Chains 50 are also secured to the rods 40 and 41 which are of such a length that the free ends will contact with the floor simultaneously with the tips 29 of the chains 25

and 27, when the bars 13 and 14 are horizontally disposed at a predetermined height 30 above the floor. The chains 50 co-operate with the chains 25 and 27 for determining in an effective manner the proper horizontal position of the device.

35

I claim:

A wheel aligner comprising a pair of bars 35 slidably mounted on each other and overlapping each other at one of their ends, means for guiding the bars, each of the bars being provided with a slot, a spring in the slot having an end secured to one bar, the other end being secured to the other bar for maintaining the over-lapping ends of the bars in close association, one of the bars being provided with a scale with the over-lapping end of the other bar movable over the scale, the other ends of the bars being provided with tire-engaging rods, a pointer 40 slidably mounted on the bar provided with a scale and movable over said scale, chains 45 carried by the last-mentioned bar and having tips at the free ends adapted to engage the floor for determining the initial horizontal position of the aligner when applied to a pair of wheels.

JOSEPH H. GRAY.
